CLAIM

The ornamental design for a night light projector, as shown and described.

DESCRIPTION

FIG. 1 is a first perspective view of a night light projector showing my new design;

FIG. 2 is a second perspective view thereof;

FIG. 3 is a third perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is an exploded perspective view of the night light projector where the night light projector is in a configuration of use.

The broken lines in the drawings depict portions of the night light projector that form no part of the claimed design.

1 Claim, 10 Drawing Sheets
